UNITED STATES PATENT OFFICE.

DAVIDSON KER TEXADA AND JENS NIELSEN OKSENHOLT, OF BOYCE, LOUISIANA.

AUTOMATIC FUEL-SAVER.

1,390,179.

Specification of Letters Patent. Patented Sept. 6, 1921.

Application filed March 10, 1921. Serial No. 451,293.

To all whom it may concern:

Be it known that we, DAVIDSON K. TEXADA and JENS NIELSEN OKSENHOLT, citizens of the United States, residing at Boyce, in the parish of Rapides and State of Louisiana, have invented certain new and useful Improvements in Automatic Fuel-Savers; and we do hereby declare the following to be a full, clear, and exact description of the invention, such as will enable others skilled in the art to which it appertains to make and use the same.

The present invention relates to improvements in automatic fuel savers, and more particularly it relates to a controlling unit for the fuel and atomizing steam valves of an oil burner for boilers which acts to open such oil and atomizing steam valves when the pressure of the steam in the boiler recedes below a predetermined limit and which acts in an opposite manner to cut down the oil and atomizing steam supply to the burner when the steam exceeds a predetermined maximum.

The invention further has for an object to provide a simply and easily regulated device forming a compact unit for carrying out the above described purposes and which is so arranged and disposed relatively to the various standard disposition of the steam and oil pipes as to be readily connected thereto and to the valves without requiring any alteration or modification in the construction of said standard parts.

With the foregoing and other objects in view, the invention will be more fully described hereinafter, and will be more particularly pointed out in the claims appended hereto.

In the drawings, wherein like symbols refer to like or corresponding parts throughout the severals views,

Figure 1 is a vertical sectional view of an automatic control device constructed according to the present invention and shown in connection with the steam and oil pipes connected to a burner and boiler indicated in dotted lines, the control device being in an initial position and the oil and atomizing steam valves being fully open; and

Fig. 2 is a similar view with the valves shown partially closed and the parts of the device in a second position.

Referring more particularly to the drawings, 1 and 2 designate respectively atomizing steam and oil pipes which lead to a

burner indicated at 3 in dotted lines and placed beneath a boiler represented at 4 having a steam supply pipe 5 leading from the dome thereof and conveying the steam to a point of application.

In the pipes 1 and 2 are valves 6 and 7 respectively provided with arms 8 and 9 in which are made slots 10 and 11 for the passage upwardly therethrough of a rod 12 having spaced apart pairs of washers or collars 13 and 14 wider than the slots 10 and 11 and acting to respectively engage above and below the arms 8 and 9.

A piston 15 is carried by the lower end of the rod 12 and is fitted to reciprocate in a cylinder 16 provided with upper and lower screw threaded heads 17 and 18, the former of which has a perforation 19 provided to slidably receive the rod 12. A coil spring 20 is wound about the rod 12 within the upper portion of the cylinder 16 and has its convolutions engaging the side wall of the cylinder, the spring at its ends engaging against the head 17 and the piston 15 respectively. The spring 20 is a relatively light spring which tends to thrust the piston 15 downwardly to the initial positions shown in Fig. 1 and to thereupon shift the valves 6 and 7 through the rod 12 and the arms 8 and 9 to a full open position, allowing the maximum quantity of oil and atomizing steam to pass the burner 3.

A second cylinder 21 is provided in conjunction with the cylinder 16 and is fitted with a reciprocating plunger 22 acted upon by the steam coming up through the base of the cylinder 21 and provided with a stem 23 entering for a distance the helices of a relatively strong coil spring 24 interposed between the plunger 22 and an adjusting follower block 25 also fitted to reciprocate in the cylinder 21. An adjusting screw 26 engages at its lower end upon the follower block 25 and is threaded through a central perforation made in the cap 27 which has removable screw threaded engagement with the upper end of the cylinder 21. The base of the cylinder 21 tapers off into a neck 28 having a valve 29 therein and connecting at its lower end with a branch of a T-coupling 30 which is included in the steam pipe 5.

The cylinders 16 and 21 are provided with extensions 31 and 32 formed with flanges 33 and 34 connected together as by bolts 35. These passages set up a communication between the two cylinders and it

will be noted that the passage 31 communicates with the cylinder 16 beneath the piston 15 when in its normal original position, while the passage 32 communicates with the 5 companion cylinder 21 above the plunger 22 which rests in its normal position beneath the passage and acts as a controlling valve to prevent the entrance of steam from normally getting into the cylinder 16.

10 Steam of course enters from the pipe 5 up through the neck 28 and into the base of the cylinder 21 beneath the plunger 22 when the valve 29 is opened. The coil 15 spring 24 acts upon the plunger 22 in opposition to the steam pressure and this spring is selected to be of such a strength and it is normally placed under such a condition of tension by the follower block 25 and adjusting screw 26 that normal steam pressures in 20 the pipe 5 will not affect the plunger 22 and the latter will consequently prevent any entrance of steam into the cylinder 16 which would affect in any way the closing of the oil and atomizing steam valves 7 and 6.

25 However, should the steam in the pipe 5 exceed its predetermined pressure it will act to raise the plunger 22 in opposition to the resistance of the coil spring 24, for instance to the position indicated in Fig. 2, thus unmasking the passage 32 and allowing the steam to get over the cylinder 16 beneath the piston 15. In proportion to the pressure of 30 the steam getting into the cylinder 16, the piston will be raised and through the rod 12 and arms 8 and 9 will act to partially or 35 fully cut off the oil and steam to the burner 3.

Of course a variety of adjustments may be had by the use of the set screw 26 and a 40 proper selection of the spring 24 so that the head of steam in the boiler 4 may be regulated in this manner. By providing a double cylinder arrangement as described in pulsations in the pressure of the steam in 45 the pipe 5 will not be apt to influence the valves 6 and 7 but will be directly taken up by the plunger 22 and compensated through the spring 24. Then again the cylinder 21 forms a regulating cylinder and the cylinder 50 16 an actuating cylinder. The regulating cylinder 21 may be entirely removed and substituted by a fresh part in case of injury or wear or where it is desirable to provide a cylinder of greater diameter or 55 greater range of adjustment or strength of spring.

All of this may be done without interfering with the actuating cylinder 16 and its connection with the arms of the valve. 60 The two cylinders form a unit which cooperate together in a simple and efficient manner and are productive of more uniform and better results than when only a single cylinder is employed.

65 It is obvious that various changes and

modifications may be made in the details of construction and design of the above specifically described embodiment of this invention without departing from the spirit thereof, such changes and modifications being restricted only by the scope of the following claims.

What is claimed is:—

1. In combination with a fuel supply conduit and a steam space, an actuating cylinder and a control cylinder, a piston in the actuating cylinder normally and yieldingly urged to an initial position therein, means whereby said piston is connected to control passage of the fuel through said conduit, a 75 plunger in said control cylinder normally cutting off steam from the actuating cylinder, and means for adjustably placing said plunger under compression in opposition to the steam pressure, substantially as described.

2. In combination with a fuel supply conduit having a valve therein, and a steam space, of a control cylinder, a piston therein, means for urging the piston to an initial position, means connecting the piston with said valve, a control cylinder in communication with the actuating cylinder and with said steam space, a plunger in the control cylinder normally held in a position to cut off 90 communication between the steam space and the actuating cylinder, and means to adjustably tension said plunger, substantially as described.

3. In combination with a fuel supply conduit having a valve therein, and a steam pipe, of an actuating cylinder, a piston reciprocating therein, resilient means for urging said piston downwardly to an initial position, a piston rod extending upwardly 105 from said piston and above the cylinder and having connection to said valve for actuating the same, a control cylinder communicating at its base with the steam pipe and through its side with the actuating cylinder 110 below said piston, a plunger in said control cylinder normally cutting off communication between the steam pipe and said actuating cylinder, resilient means for holding said plunger in initial position, and means for 115 imposing variable tension on said plunger, substantially as described.

4. In combination with oil and atomizing steam conduits having valves therein, an actuating cylinder, a piston therein, a rod connected to the piston and connected to actuate said valves, resilient means in the cylinder urging said piston to an initial position to hold the valves open, a control cylinder 125 communicating at its base with the steam conduit and through its side wall with the actuating cylinder beneath the piston therein, a plunger in the control cylinder acted upon by the steam pressure beneath, relatively heavy resilient means acting upon the 130

upper side of said plunger, a follower block on the resilient means, and an adjusting device acting upon said follower block to control the compression to which said resilient means is subjected, substantially as described.

5. In combination with a boiler and a fire box having an oil burner therein, oil and atomizing fluid pipes connected with said burner and provided with valves therein, and a steam pipe connecting with the same sides of the boiler, of a unitary control device for the burner comprising a control cylinder, a piston therein, a rod extending

from the piston and coupled to actuate said valves, a spring in the cylinder urging said piston to an initial position to hold the valves open, a control cylinder situated close to said actuating cylinder and in communication through the side therewith, said control cylinder also connected to said steam pipe, a piston in the control cylinder, a heavy coil spring thereabove, a follower above the coil spring, and an adjusting screw engaging said follower, substantially as described.

DAVIDSON KER TEXADA.
